UNITED STATES PATENT OFFICE.

JACOB BLASZCZYK, OF CHIPPEWA FALLS, WISCONSIN.

SLED-BRAKE.

1,244,460.

Specification of Letters Patent. Patented Oct. 30, 1917.

Application filed March 15, 1917. Serial No. 154,988.

To all whom it may concern:

Be it known that I, JACOB BLASZCZYK, a subject of the Emperor of Russia, residing at Chippewa Falls, in the county of Chippewa and State of Wisconsin, have invented 5 certain new and useful Improvements in Sled-Brakes, of which the following is a specification.

This invention relates to certain new and 10 useful improvements in sled brakes.

The primary object of the invention is the provision of an attachment for hand sleds whereby the occupant thereof may readily retard the onward movement of the 15 sled without interfering with the steering of the same, the structure being easy and inexpensive to manufacture.

A further object of the device is to provide a brake member adapted for engaging 20 the road-bed at a point beneath a sled and operable from a point above the forward portion thereof, the same being readily actuated by the occupant of the sled and thereafter automatically returned to its normal 25 inoperative position.

In the drawing forming a part of this application and in which like designating characters refer to corresponding parts throughout the several views:

30 Figure 1 is a central vertical longitudinal sectional view of a sled provided with the present device, the same being illustrated by dotted lines in its operative position.

Fig. 2 is a top plan view thereof with 35 the top board broken away.

Fig. 3 is an enlarged sectional view of the foot actuating means of the device.

Fig. 4 is a longitudinal sectional view of 40 a modified form of foot-actuating member, and,

Fig. 5 is a vertical sectional view taken upon line V—V of Fig. 4.

The present arrangement is adaptable for different forms of sleds, the same being 45 herein illustrated in connection with a hand sled having opposite runners 11 and a deck or top board 12 of substantially the usual construction. A T-shaped brace iron 13 is arranged forwardly of the sled consisting 50 of a cross bar 14 connecting together the upper ends of the runners 11 and secured thereto by screws 12', to which bar a drawing rope (not shown) is adapted to be secured while the feet or hands of the occupant 55 who is seated upon the sled top 12 may readily engage the bar 14 as the same

is spaced considerably forwardly of the front edge 15 of the top board 12.

The said brace iron has a rearwardly projecting member arranged perpendicular to 60 the bar 14 consisting of parallel strips 16 having their rear ends attached by bolts 17 to the board 12 while guides 18 are arranged beneath the strips 16 in parallelism therewith, with their forward ends secured beneath the bar 14 and with their rear ends connected to the lower ends of the aforementioned bolts 17 upon the under face of the board 12.

The brake proper consists of a substantially rectangular frame 19 hinged to a plate 20 secured substantially centrally beneath the top board 12 of the sled and between the runners 11 thereof, a toothed plate 21 being carried by the free end of the frame 19 70 adapted for engagement with the road-bed such as 22, when the said frame is swung downwardly.

A post 23 is arranged substantially upright between the strips 16 having a cross 80 handle 24 at its upper end while the lower end of the post is pivotally connected by means of a rod 25 with a central crank portion 26 of the frame 19. A hub 27 is centrally provided upon the post 23 having oppositely projecting spindles 28 upon which anti-friction sleeves or rollers 29 are journaled adapted to travel upon the guides 18 beneath and in contact with the strip 16, retaining washers 30 being arranged upon 90 said spindles for the said rollers.

A helical spring 31 encircles the rod 25 having its rear end anchored as at 32 to the plate 20 while the forward end of said spring is looped around the post 23.

With an occupant seated upon the top 12 of the sled 10 and its feet positioned adjacent the bar 14 with the brake mechanism held in its normal elevated inoperative position by the spring 31, the feet of the operator may be readily positioned upon the handle 24 and said handle forced forwardly carrying the post 23 and the rod 29 in a corresponding direction, thereby lowering the frame 19 with the plate 21 in engagement with the road-bed 22, as indicated by dotted lines in Fig. 1 of the drawing. Upon releasing the handle 24, the spring 31 automatically returns the said post and handle as well as the rods 25 rearwardly and the 105 frame 19 upwardly. It will be understood that the post 23 may become slightly tilted

during the operation of the device without in any manner interfering with the actuation of the brake frame 19 while the positioning of the spring 31 upon the rod 25 5 acts as an actuating means and giving the structure greater strength and compactness without interfering with the perfect operation of the return mechanism. It will be understood that the brake may also be operated by the hands of the operator upon 10 grasping the cross handle 24 whenever the position of the occupant of the sled renders the same convenient during the use thereof.

In the modified form of the device illustrated in Figs. 4 and 5 of the drawing, a portion of a sled top 12' is illustrated in connection with which a single strip 16' and guide 18' arranged therebeneath are provided, attached to the board 12' by bolts 17'. 15 A handle 24' is arranged in the form of a rectangular member having the lower side 34 positioned between the strip 16' and guide 18' with anti-friction rollers 35 interposed therebetween. A strap 36 is carried by said lower member 34 surrounding the guide 18' and having an anti-friction roller 37 therein while a depending lug 38 20 is carried by the strap to which the operating rod 25' of the brake mechanism is pivotally connected, the said rod being provided with a return spring 31'. The modified form of construction is operable similar 25 to the arrangement herein fully described and a further description thereof is believed to be unnecessary.

What I claim as new is:—

1. A brake for a sled comprising a ground-engaging member hinged therebeneath, a slidable actuator arranged adjacent 40 the forward end of the sled, pivotal connections between the said actuator and said ground-engaging member, and automatic return means therefor.

2. In attachment for a sled having side 45 runners and a top, a T-shaped brace-iron forwardly carried thereby attached to the said top and runners, a road-bed engaging member hinged to said top beneath the said runners, and an actuator therefor opera-

tively connected thereto slidably attached 50 to the said brace-iron.

3. An attachment for a sled having side runners and a top, a T-shaped brace-iron forwardly carried thereby attached to the said top and runners, a road-bed engaging 55 member hinged to said top beneath the said runners, a post slidably carried by the said brace-iron and operable in its forward slide- 60 able movement, an operating handle for the said post, a rod pivotally connected between the said post and road-bed engaging member, and automatic return means for said member.

4. In combination with a sled having side runners and a top, a T-shaped brace-iron 65 connecting the forward ends of the runners and having parallel strip portions attached to the said top, guides arranged beneath the said strip portions, an upright post between the said guides, anti-friction journaling 70 means for said post between the said strips and guides, an operating handle upon the upper end of said post, a retarding member hinged beneath said top between the said runners, and pivotal connections between 75 the said retarding means and the lower end of said post.

5. In combination with a sled having side runners and a top, a T-shaped brace-iron connecting the forward ends of the runners 80 and having parallel strip portions attached to the said top, guides arranged beneath the said strip portions, an upright post between the said guides, anti-friction journaling means for said post between the said 85 strips and guides, an operating handle upon the upper end of said post, a retarding member hinged beneath said top between the said runners, a rod pivoted between the said post and retarding means, and a re- 90 turn spring for said retarding means encircling the said rod having one end attached to said post at its rear end anchored adjacent the hinging point of said retarding means.

In testimony whereof I affix my signature.

JACOB BLASZCZYK.
